UNITED STATES PATENT OFFICE.

MICHAEL BRASSILL, OF HARTFORD, CONNECTICUT.

CANDLESTICK.

SPECIFICATION forming part of Letters Patent No. 236,873, dated January 25, 1881.

Application filed May 22, 1880. (No model.)

To all whom it may concern:

Be it known that I, MICHAEL BRASSILL, of Hartford, in the county of Hartford and State of Connecticut, have invented an Improved 5 Candlestick, of which the following is a description, reference being had to the accompanying drawings, where—

Figure 1 is a side view. Fig. 2 is a top view. Fig. 3 is a view in central vertical section; 10 Fig. 4, side view of match-case.

The invention relates to a candlestick which has a candle-receptacle formed of elastic fingers appropriate to candles of different diameters, and also has a case for matches contained 15 within a hollow pillar supporting the candle-receptacle.

The invention consists, first, in a hollow pillar bearing a candle-receptacle permanently fixed to a suitable base-plate, combined with 20 a match-case which is separate from both pillar and base-plate, and is introduced into the pillar through an opening in the base-plate, and kept there by spring or other suitable catches, and is readily removable to expose 25 the matches at pleasure; second, in the combination of the separate and removable match-case, the permanently-attached base and hollow pillar, the candle-receptacle borne on top of the pillar, and a guard-plate interposed between the pillar and the candle-receptacle to 30 intercept melted candle-matter and prevent it from running down the side of the pillar.

The letter *a* denotes the base-plate, raised centrally to give space for the handles of the 35 catches appurtenant to the match-case, and provided with the central orifice, *b*, forming a mouth or opening to the inside of the hollow pillar. The base-plate projects into the hol-

low of the pillar to form a flange, *a'*, for the catches just mentioned to take hold of. 40

The letter *c* denotes the hollow pillar permanently fixed to the base-plate, and bearing on its top the spring-fingers *d*, formed into a candle-receptacle, with their upper ends turned outward, that they may not scrape the surface 45 of a candle thrust into their embrace, and with intervals *e* left between them at their lower ends, to allow the escape of melted candle-matter and to facilitate the cleaning of the receptacle. 50

The letter *f* denotes a guard-plate interposed between the top of the hollow pillar and the bottom of the candle-receptacle, to intercept melted candle-matter and prevent it from running down the side of the pillar. 55

The letter *g* denotes the match-case, ordinarily kept within the hollow pillar, and there retained by the spring-catches *h h*.

The letter *i* denotes a roughened space on the match-case for lighting matches. 60

I claim as my improvement—

1. In combination, the candle-receptacle permanently attached to the hollow pillar, the hollow pillar permanently attached to the base-plate, the base-plate provided with the central orifice, and the match-case, with its catches, all substantially as described. 65

2. In combination, the candle-receptacle, the guard-plate, the hollow pillar, the base-plate fast to the pillar and provided with the central orifice, and the match-case, with its catches, all substantially as described. 70

MICHAEL BRASSILL.
